US00D907290S

(12) **United States Design Patent** (10) **Patent No.:** **US D907,290 S**
(45) **Date of Patent:** **** Jan. 5, 2021**

(54) **ELECTRONIC CIGARETTE**

(71) Applicant: **SHENZHEN SMOORE TECHNOLOGY LIMITED,**
Guangdong (CN)

(72) Inventor: **Weidong Pan**, Guangdong (CN)

(73) Assignee: **SHENZHEN SMOORE TECHNOLOGY LIMITED**, Shenzhen (CN)

(**) Term: **15 Years**

(21) Appl. No.: **29/712,683**

(22) Filed: **Nov. 11, 2019**

Related U.S. Application Data

(63) Continuation of application No. 29/646,040, filed on May 1, 2018, now Pat. No. Des. 875,302.

(57) **CLAIM**

The ornamental design for an electronic cigarette, as shown and described.

DESCRIPTION

FIG. 1 is a front elevational view of an electronic cigarette shown as a portion removed from the assembly for clarity of disclosure;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, right, and bottom perspective view thereof; and

FIG. 8 is a rear, left, and top perspective view thereof.

FIG. 9 is a front elevational view of the electronic cigarette shown in an assemble configuration of use;

FIG. 10 is a rear elevational view thereof;

FIG. 11 is a left side elevational view thereof;

FIG. 12 is a right side elevational view thereof;

FIG. 13 is a top plan view thereof;

FIG. 14 is a bottom plan view thereof;

FIG. 15 is a front, right, and bottom perspective view thereof; and,

FIG. 16 is a rear, left, and top perspective view thereof.

The broken lines in the figures are included for the purpose of illustrating portions of the electronic cigarette which form no part of the claimed design.

1 Claim, 15 Drawing Sheets
